THERMOSTAT REGULATING APPARATUS

William B. Mackintosh, Knoxville, Tenn., assignor to The Fulton Sylphon Company, Knoxville, Tenn., a corporation of Delaware

Application December 28, 1931, Serial No. 583,532

16 Claims. (Cl. 236—1)

This invention relates to a temperature regulating apparatus and more particularly to a temperature regulating apparatus for controlling the flow of fuel to a consuming device.

5 It has heretofore been proposed to control the flow of fuel to a consuming device by means of a thermostatically operated valve, in which the motor of such thermostat is governed by the heat of a pilot flame. However, in these constructions, 10 when the pilot flame becomes extinguished, the fuel can escape through the pilot burner, which may cause serious consequences when the pilot burner is relighted.

One of the objects of the present invention is to 15 provide a novel device for regulating the flow of fuel to a consuming device, which is governed by the temperature of a pilot flame and controlled by changes in temperature of the medium to be controlled such as ambient temperatures.

20 Another object of the present invention is to provide a novel device for regulating the flow of fuel to the main burner of a consuming device which is actuated by changes of temperature when subjected to the temperature of a pilot flame, but which shuts off the flow of fuel to both the main burner and pilot burner when the pilot flame becomes extinguished.

Another object of the present invention is to 25 provide a novel device combining a control for the flow of fuel and a safety control for a pilot light which prevents the escape of the fuel when the pilot flame is extinguished, but which may be manually operated to supply fuel to the pilot burner for starting purposes.

30 Another object of the present invention is to provide a novel fuel controlling device which is simple and compact and efficient for the purpose intended.

These and other objects will become apparent 35 from the accompanying description and drawing in which like reference characters denote like parts throughout the several views. It is to be expressly understood, however, that the drawing is for the purpose of illustration only and not a 40 definition of the limits of the invention, reference being had for this purpose to the appended claims.

In the drawing,

Fig. 1 is a side elevational view in section of a 45 fuel controlling device incorporating the present invention, the section being taken on lines 1—1 of Fig. 2;

Fig. 2 is a cross-sectional view through the device shown in Fig. 1, and taken on lines 2—2 of Fig. 1;

5 Fig. 3 is a side elevational view in section of the

valve mechanism shown in Fig. 1, taken on lines 3—3 of Fig. 2.

The illustrated embodiment includes in its general organization a valve mechanism 4 for regulating the flow of fuel from a supply conduit 5 to a main burner of a consuming device (not shown) through outlet conduit 6, and to a pilot burner 7. The valve mechanism is actuated by a thermostatic motor 8, which is governed by the pilot burner 7, and in case of failure of the pilot 10 burner to keep the motor hot, the valve will automatically close communication between the supply conduit 5 and both the main and pilot burners. The motor 8 is controlled by a thermostat unit 9 which injects a fluid into the motor 15 upon increases in temperature and abstracts the fluid from the motor upon decreases in temperature of the medium to be controlled. However, the thermostat unit 9 is effective to control the motor only when the governing pilot burner has 20 properly conditioned the motor 8.

The valve mechanism as shown includes a two-part casing 10 and 11 with the part 11 forming a support for the motor 8. The casing 10 is of a generally cylindrical contour with an annular recess open at its upper side, and intersected by an apertured web 12 forming an annular valve seat 13. The casing part 11 is provided with an annular rib 14 adapted to fit into the open side of the recess in the casing part 10 for closing the casing 30 and forming a second valve seat 14 vertically spaced from the valve seat 13. The two parts of the casing 10 and 11 are mechanically held in position by any suitable means such as bolts (not shown). A disk-like valve member 15 is positioned in the casing between the valve seats 13 and 14. The interior of the casing provides an admission chamber 16 above the annular seat 14, a valve chamber 17 between the annular seats 13 and 14 and an outlet chamber 18 below the annular seat 13. The valve member 15 is of less diameter than the interior of the casing 10 for allowing a flow of fuel to pass the valve when in an intermediate position, and is also limited in its movement by cooperation with one or the other of 45 the valve seats 13 or 14.

On opposite sides, the casing part 10 is provided with any suitable means, such as internally threaded hollow bosses 19 and 20, for connection with the conduits 5 and 6 respectively. 50 Communication is established between the inlet conduit 5 and the admission chamber 16 by means of a passageway 21 formed in the casing member 11, a wall 22 being provided between the hollow boss 19 and the interior of the casing, 55

while the hollow boss 20 is in direct communication with the outlet chamber 18. On the periphery of the casing 10 intermediate the bosses 19 and 20 a third hollow boss 23 is provided, which 5 directly communicates with the valve chamber 17. An outlet conduit 24 for the pilot burner 7 is connected to this boss 23 by any suitable means, illustrated as a compression coupling 25.

An actuating valve stem 26 is connected with 10 the valve centrally thereof and extends from one side of the valve through an aperture in the casing member 11. On the other side of the valve a coil spring 27 is positioned between the valve 15 and the casing 10, normally tending to hold the 15 valve against the annular seat 14, bosses 28 and 29 being provided on the valve and casing respectively, for properly positioning the spring. In the construction thus far described, the valve 15 when held against the valve seat 14 by the 20 spring 27 prevents the fuel, entering from the conduit 5 through the passageway 21 and into the admission chamber 16, from entering the valve chamber 17, and the supply of fuel is cut off to both the main burner and auxiliary pilot burner. When the main valve engages the 25 annular seat 13 the fuel in the admission chamber 16 may enter the valve chamber 17 and supply the pilot burner 7 through the conduit 24 but the fuel is shut off from the conduit 6 and the main burner. In any intermediate position of the 30 valve 15 between the seats 13 and 14, fuel will be supplied to both the conduits 6 and 24 from the valve chamber.

For starting the apparatus in operation it is 35 necessary to establish a communication between the admission chamber 16 and the conduit 24 to supply fuel to the pilot burner. To this end a bypass 30 is provided between the admission chamber 16 and the hollow boss 23, which is similar 40 to the passageway 21 and is formed in the casing member 11. This by-pass 30 terminates in a valve seat 31 and enters the hollow boss 23 which, as previously described, opens into the conduit 24. This by-pass is held in a normally closed 45 condition by a conical valve head 32 engaging the valve seat 31. The valve 32 is held in position by a spring 33 engaging a recess in the casing 4 at one end, and the valve head 32 at the other end. A valve stem 34 connected with the 50 valve head 32 extends outwardly through the casing 10 and at its outer end is provided with a handle 35 so that the valve 32 may be manually actuated against the action of the spring 33 to open communication between the admission 55 chamber 16 and the conduit 24 when the main valve 15 is held in engagement with the annular seat 14 by the spring 27.

The motor element 8 for actuating the valve 15 includes an actuating member illustrated as 60 a closed vessel having a rigid wall 36 enclosing a flexible bellows 37. The outer end of the bellows is connected to the rigid wall 36 by an intermediate collar 38 while the inner end of the bellows is provided with a movable head 39, the 65 wall and bellows being spaced by the collar 38 to form an expansion chamber therebetween. The valve stem 26 extending through the aperture in the casing part 11 is rigidly connected with the movable head 39 of the bellows so that 70 movement of the head 39 is directly transmitted to the valve 15. A coil spring 40 surrounds the stem 26 for augmenting the action of the spring 27 and assisting in holding the bellows in its proper position.

75 The rigid casing 36 and collar 38 are connected

to and supported by a surrounding casing 41, by any suitable means such as welding, and the casing 41, in turn, is fixed to and supported by the casing part 11. The casings 36 and 41 are so shaped as to provide a heating chamber therebetween which entirely surrounds the operating element of the motor. Connected with this heating chamber, as by means of a conduit 42 welded to the side wall of the casing 41, is a heating bulb 43 positioned in the path of the pilot burner 10 flame and containing a vaporizable medium such as water adapted to transmit heat when vaporized from the pilot flame to the motor element. In order to prevent the pressure in the heating chamber from becoming excessive, a condenser 15 in the form of a tube 44 secured to the casing 41 and having a series of fins 45, is provided for transmitting heat to the surrounding atmosphere. In this manner heat is supplied to the heating medium at a constant rate and dissipated to the surrounding atmosphere at a predetermined rate depending upon the temperature differential between the two mediums, so that a desired temperature constant is maintained in the heating chamber. This desired temperature 20 is such that a thermosensitive fluid in the motor will be vaporized and actuate the bellows when the pilot flame is functioning properly but the thermosensitive fluid will not be vaporized if the pilot flame becomes extinguished. Although 25 otherwise illustrated in the drawings for purposes of convenience, the conduit 42 and heating bulb 43 are preferably positioned below the lowest point in the heating chamber 41 so that the condensate of the heating medium will by gravity 30 flow back into the bulb.

The thermostatic unit 9 is connected by means of a tube 50 with the motor unit of the apparatus, the tube extending through casing 41 and casing 36, being secured to both to form a tight connection. The thermostat unit may be of any suitable construction but as shown comprises a base plate 51 adapted to be attached to any suitable support, as by means of screws 52, so as to be positioned in the medium to be controlled. This 45 base plate 51 is centrally apertured as at 53 to receive a flexible bellows 54 having a movable head 56 and a stationary head 55, the latter being shown as provided with an apertured boss to receive the tube 50, which boss may also be extended to form a stop within the bellows. Between the stationary head 55 and the movable head 56 a coil spring 57 is provided for holding the bellows in a normally extended position. This bellows is held in position within the aperture 53 by means of a bar 58 pivoted to the base 51 at one end and adapted to be swung into position under the stationary head 55, a slot 59 being provided in the bar to receive the boss on the head 55. This bellows is adapted to contain 60 the thermosensitive fluid which is injected into the motor unit 8 and when heated by the surrounding medium actuates the valve 15.

An actuating unit for the bellows 54 is adjustably mounted on a shoulder 60 of the base 61 51 as by means of a screw threaded connection and includes an inner casing part 61 centrally apertured and forming a rigid support for one end of a bellows 62 having a movable head 63. An outer casing part for the actuating unit includes a surrounding shell 64 fixed to the inner shell in any suitable manner, as by welding, and forms a closed chamber between the inner shell and bellows 62. A depending skirt on the unit is provided with screw threads for engagement with 71

screw threads on the shoulder 60 of the base. An abutment 65 extending from the movable head of the bellows 63 is provided for engagement with the movable head 56 of the bellows 54, and is 5 shown as formed by a tubular element carried by a boss on said head 56. This boss is centrally bored as at 65' for initially charging the unit with a thermosensitive fluid which is effective within the temperature range to be controlled by 10 the apparatus. After the initial charge has been placed in this chamber and sealed and the unit screwed to an adjusted position on the shoulder 60 of the base 51, the abutment 65 acts as an actuating means for the bellows 63. The exact 15 temperature at which it is desired to initially operate the apparatus may be predetermined by rotating the unit on the base 51 so as to require a greater or less expansion, as the case may be, of the bellows 62 before the abutment 65 engages the head 56 of the bellows 54.

The operation of the apparatus is as follows:— As a starting condition let it be assumed that neither the main burner nor the pilot burner are lighted, that the heating chamber is cold, and 25 the medium whose temperature is to be controlled is cold, at which time the valve 15 will be seated against the annular valve seat 14 by the spring 27 and communication between the admission chamber 16 and both of the outlet conduits 6 30 and 24 entirely shut off. The apparatus is then started in its operation by manual actuation of the valve head 32 by means of the handle 35 and against the action of the spring 33, allowing a communication between the admission chamber 35 16 and conduit 24 leading to the pilot burner through the by-pass 30, and the fuel is ignited at the burner 7. This pilot burner 7 is adjacent the main burner and also in position to heat the bulb 43. As soon as the bulb 43 is heated, the 40 heating medium within the bulb will be vaporized and flow through the conduit 42 into the heating chamber between the casing 36 and 41 causing a small residual charge of the less volatile thermosensitive fluid in the motor chamber 8 to be vaporized and to move the valve 15 to the position shown in Fig. 1. The fuel then flows from the conduit 5 through the admission chamber 16, valve chamber 17, between the exterior diameter of the 45 valve 15 and the interior diameter of the casing 4 to the outlet chamber 18, and then through the conduit 6 to the main burner which will immediately be ignited by the pilot burner 7. The manually operated valve 32 may then be released, and by the spring 33, will close communication 50 between the by-pass 30 from the admission chamber 16 to the conduit 24, and the fuel will then be supplied to the pilot burner from the valve chamber 17 and through the outlet connection 23 to the conduit 24. As the main burner increases the temperature of the medium to be 55 controlled, the thermostatic unit 9 will be actuated. Temperature increases acting on the thermostat 9 will cause the head 63 to be moved to the left as shown in Fig. 1 until such time as the abutment 65 engages the head 56 of the bellows 54 and forces a small quantity of the volatile thermosensitive fluid contained therein through the tube 50 and into the motor chamber of the motor 8. The heat of the chamber surrounding 60 the motor chamber immediately vaporizes the thermosensitive fluid and causes the movable head 39 to act against the tension of the springs 27 and 40 to move the valve 15 toward the annular valve seat 13 and throttle the flow of fuel to the main burner. If the temperature of the me-

dium to be controlled continues to increase more of the volatile thermosensitive fluid will be forced into the motor chamber and the valve 15 will be moved in accordance therewith; until it is finally seated on the annular valve seat 13 shutting off communication between the valve chamber 17 and the outlet chamber 18, extinguishing the flame of the main burner, but allowing a flow of the fuel through the conduit 24 to the pilot burner 7. As the temperature of the medium to be controlled decreases the spring 57 will move the head 56 with the receding abutment 65 and create a partial vacuum in the tube 50 and chamber of the motor 8 so that part of the thermosensitive fluid in the chamber will be moved back toward the 15 bellows 54 and become condensed, until such time as the valve 15 again opens and allows the fuel to flow to the main burner to be immediately ignited by the pilot burner 7. However, if the pilot burner becomes extinguished, the condenser 20 quickly dissipates the heat in the heating chamber, and the thermosensitive fluid in the motor chamber 8 condenses, allowing the springs 27 and 40 to move the valve 15 against the annular valve seat 14, to shut off all communication between the admission chamber 16 and both the main burner and pilot burner, preventing any liability of damage by explosion caused by leakage and accumulation of fuel from the pilot burner 7.

The motor is maintained in an operative condition to be actuated by changes in temperature of the ambient, as long as the pilot burner remains ignited, and becomes inoperative when the pilot burner becomes extinguished, but in order to prevent excessive pressure in the chamber between the casings 36 and 41, and to maintain the actuating element of the motor at a substantially constant operating condition, the condenser is provided. The radiating surface 45 of the condenser is such that it will dissipate heat at a rate 30 proportionate to the heat transmitted to the motor. In this manner the motor is maintained at a substantially constant operating condition which prevents any changing temperature condition of the motor which might affect the proper 35 operation of the thermostat.

It will now be apparent that an efficient, simple and compact apparatus has been provided for controlling the flow of a fuel to a main burner, which is actuated in accordance with the temperature of the medium to be controlled only when the pilot burner is lighted. It will be further apparent that the apparatus combines such a controlling device with safety features that prevent the escape of the fuel when the pilot 40 flame is extinguished and liability of dangerous 45 consequences.

It will also be apparent to those skilled in the art that various changes may be made in the size, shape and details of construction without departing from the spirit of the present invention. Any other suitable type of thermostat, heating means for the motor chamber, condenser or connecting means may be used in place 50 of those described, and in some cases the condenser may be entirely eliminated, without departing from the spirit of the invention. It will also be perceived that the invention may be embodied in devices for controlling the temperature 55 of a variety of mediums and that the thermostat may be subjected to liquid as well as to gaseous 60 mediums the temperatures of which are to be controlled. The embodiment disclosed and illustrated in the drawings does not, therefore, de- 65 70 75

fine the limits of the present invention and reference is to be had to the appended claims.

What is claimed is:—

1. In a fuel control device, an expandible and contractible motor for varying the flow of fuel to a main burner, an auxiliary burner governing the operation of the motor, a thermostat for controlling the motor when put in an operative condition by the governing means, and means for stopping the flow of fuel to both the main and auxiliary burners when the flame of the auxiliary burner is extinguished.
2. In a fuel control device, a valve, an expandible and contractible motor for actuating the valve and varying the flow of fuel to a main burner, an auxiliary burner governing the operation of the motor, a thermostat for controlling the motor when put into an operative condition by the governing means, means for closing the valve and stopping the flow of fuel to both the main and auxiliary burners when the flame of the auxiliary burner is extinguished, and a manually controlled by-pass for supplying the auxiliary burner with fuel when the valve is closed.
3. In a fuel control device for a heating apparatus having a main and a pilot burner, a valve for controlling the flow of fuel, means for normally actuating the valve to vary the flow of fuel to the main burner in accordance with the temperature of the medium to be controlled, said means including a motor element operated by fluid pressure, means for rendering said motor element capable of generating an effective vapor pressure only when said pilot burner is ignited, and a second means for actuating the valve to a position to stop the flow of fuel to both the main and pilot burners when the flame of the pilot burner is extinguished.
4. In a fuel control device, an expandible and contractible motor for varying the flow of fuel to a main burner, a chamber surrounding the motor, an auxiliary burner for heating the chamber and governing the motor, a thermostat for controlling the motor when heated by the auxiliary burner and chamber, and means for stopping the flow of fuel to both the main and auxiliary burners when the flame of the auxiliary burner is extinguished.
5. In a fuel control device, an expandible and contractible motor for varying the flow of fuel to a main burner, a chamber surrounding the motor, an auxiliary burner adjacent the main burner, a bulb containing a fluid positioned in the flame of the auxiliary burner, a conduit connecting the bulb and chamber for transmitting heat from the auxiliary burner to the chamber and governing the operation of the motor, a thermostat for controlling the motor when heated by the auxiliary burner, and means for stopping the flow of fuel to both the main and auxiliary burners when the flame of the auxiliary burner is extinguished.
6. In a fuel control device, a main burner, an auxiliary burner, an expandible and contractible motor for stopping the flow of fuel to the main burner in one extreme position and to both the main and auxiliary burner in another extreme position but varying the flow of fuel to the main burner in intermediate positions, means for governing the operation of the motor in accordance with the condition of the auxiliary burner, a thermostat for controlling the motor to vary or stop the flow of fuel to the main burner when put in an operative condition by the governing means, and means for actuating the motor to

stop the flow of fuel to both the main and auxiliary burners when the flame of the auxiliary burner is extinguished.

7. In a fuel control device, mechanism for varying the flow of fuel to a main burner, a chamber surrounding the mechanism, an auxiliary burner for heating the chamber, a thermostat for controlling the mechanism when the chamber is heated by the auxiliary burner, and means for stopping the flow of fuel when the flame of the auxiliary burner is extinguished.

8. In a fuel control device for a heating apparatus having a main and a pilot burner, valve mechanism for stopping the flow of fuel to the main burner in one extreme position and to both the main and pilot burners in another extreme position but varying the flow of fuel to the main burner in intermediate positions, a thermostat including a motor vessel adapted to be actuated by vapor pressure for normally actuating the valve mechanism to vary or stop the flow of fuel to the main burner in accordance with the temperature of the medium to be controlled, heating means for rendering said motor vessel capable of generating a vapor pressure to actuate said valve mechanism only when said pilot burner is ignited, and mechanism to actuate the valve mechanism to a position to stop the flow of fuel to both the main and pilot burners when the flame of the pilot burner is extinguished.

9. In a fuel control device, a valve, an expandible and contractible vessel for actuating the valve, an auxiliary burner for heating the vessel, means actuated by an increase in temperature for injecting a quantity of thermosensitive fluid into the vessel, said vessel when heated by the auxiliary burner controlling the flow of fuel to the main burner, and means for stopping the flow of fuel when the flame of the auxiliary burner is extinguished.

10. In a fuel control device, a main burner, an auxiliary burner, a valve operable in one extreme position to stop the flow of fuel to both the main and auxiliary burners and in another extreme position to stop the flow of fuel to the main burner only, a hot vessel for actuating the valve, means for transmitting heat from the auxiliary burner to the vessel and governing the operation of the valve, means actuated by an increase in temperature for controlling the operation of the valve from one extreme position to the other, and means for moving the valve to cut off the flow of fuel to both the main and auxiliary burners when the flame of the auxiliary burner is extinguished.

11. In a fuel control device, a casing having inlet and outlet sides with a valve seat between, a main burner and an auxiliary burner connected to the outlet side of said casing, a valve cooperating with the valve seat, a closed vessel having a movable wall connected to the valve, a heating means surrounding the vessel and subjected to the temperature of the auxiliary burner, and means actuated by increases in temperature for injecting small quantities of a liquid thermosensitive fluid into the hot vessel.

12. In a fuel control device, a casing having an inlet chamber, an outlet chamber and an intermediate valve chamber, a pair of spaced valve seats in the valve chamber, a valve cooperating with the valve seats, a main burner in communication with the outlet chamber, an auxiliary burner communicating with the valve chamber, a closed vessel having a movable wall for controlling the valve, means for surrounding the

5 vessel with a heated medium and subjected to the heat of the auxiliary burner, and means actuated by increases in temperature for injecting small quantities of a liquid thermosensitive fluid into the hot vessel whereby said liquid when vaporized will move the movable wall and actuate the valve.

13. In a fuel control device, a thermostat for varying the flow of fuel to a main burner including a bellows, a heating jacket surrounding the bellows and containing a heat transmitting medium, an auxiliary burner for heating the bellows through the heat transmitting medium, means for dissipating the heat in the medium at a substantially constant rate so that the temperature of the bellows may be maintained substantially constant, means subjected to the temperature variations for injecting a thermosensitive fluid into the hot bellows upon a temperature increase, and means for discontinuing the flow of fuel to both the main and auxiliary burners when the flame of the auxiliary burner is extinguished.

20 25 14. In a fuel control device, a valve for controlling the fuel flow, a motor for operating said valve, a heating chamber surrounding said motor, a thermostat for developing pressure in

said motor when said motor is hot, an auxiliary burner, and heating means subjected to said auxiliary burner and communicating with said heating chamber for rendering said motor operative.

15. In a fuel control device, a valve, a motor for operating said valve, a thermostat for injecting a vaporizable liquid into said motor upon changes of temperature, a chamber for heating said motor to render said thermostat effective 10 to actuate said valve, and means including a container for a heating medium subjected to a flame maintained by said fuel and communicating with said chamber to heat said chamber and render said motor operative.

15 16. In a controlling device for a heating medium, a valve for controlling the flow of heating medium, an expandible and contractible motor vessel operatively connected to said valve, a heating chamber surrounding said motor vessel, 20 thermostatic means for injecting a vaporizable liquid into said motor vessel, means for heating said heating chamber, and means for closing said valve when the temperature of said heating chamber is insufficient to vaporize said liquid in 25 said motor vessel.

WILLIAM B. MACKINTOSH.
